THREAD CLEANING DEVICE

Albert G. Osborne, Paterson, and Bertrand H. H.
Noble, Glen Rock, N. J.

Application August 23, 1935, Serial No. 37,460

6 Claims. (Cl. 28—70)

This invention relates to improvements in thread cleaning devices, the principal object of the invention being to provide an improved device of this character by means of which the entire 5 surface of the thread will be cleaned in a single operation.

In the textile art, it is common practice, as a preliminary to the weaving and knitting of threads into fabrics, to subject the individual 10 threads to a cleaning operation in order to remove enlargements caused by foreign matter and thereby render the threads uniform in diameter so as to avoid imperfections in the finished fabric. This cleaning is usually done by running the 15 thread through a slot formed in a metal plate. A disadvantage of this type of cleaner is that the thread is cleaned only on two opposite sides and consequently after passing through the cleaner is more or less flat in cross-section. We 20 are aware that attempts have been made to overcome this disadvantage, but such attempts have resulted only in greatly complicating the structure of the cleaning device. By means of the present invention, not only is the disadvantage 25 above referred to completely overcome and the entire surface of the thread cleaned, but the simplicity of construction of the device is maintained.

Other objects and advantages of the invention 30 will be apparent as the description proceeds.

In the drawing accompanying this specification,

Figure 1 is a perspective view of a preferred 35 embodiment of a device constructed in accordance with the present invention;

Figure 2 is a sectional view taken approximately on the line II—II of Figure 1;

Fig. 3 is an enlarged detail sectional view of a 40 portion of the cooperating thread-cleaning members.

The device as illustrated herein embodies a base member or block 1 provided at its underside with a recess of inverted V-shape for engagement with the traverse rail (not shown) of the usual 45 winding or other machine. It will be understood that in the usual type of winding machines with which the device is intended to operate, a number of threads are spooled at one time, thus necessitating employment of a corresponding 50 number of cleaning devices, all of which are secured on the traverse rail of the machine.

An arm 2 of L-shape in cross-section extends 55 at right angles from one side of the block 1 and is provided at its free end with an opening into

porcelain thread guides 3, a similar thread guide 4 being similarly mounted in the block 1 in alignment with the guide 3.

The cleaning device proper is disposed in the angle formed between the block 1 and the arm 2, 5 and comprises a member bent upon itself to form a loop portion 5 and a pair of legs 5^a in parallel relation to each other. The member 5, 5^a is preferably made of cold rolled steel case hardened throughout, and is secured to the vertical web of 10 the arm 2 by means of screws 6, one of which is shown in Figure 2. The elasticity of the cleaning member is such that the legs 5^a tend to separate slightly for a purpose hereinafter described, means being provided for normally maintaining 15 the opposing faces of the legs in abutting relation for a portion of their length. Such means in the present instance comprises a screw 7 which passes freely through one of the legs 5^a and is threaded at one end into the other leg. The 20 screw is provided at its opposite end with an operating lever 8 secured against rotation on the screw and retained in position by a pair of nuts 9 and 10. A second lever 11 carries a hub 12 which is threaded on the screw 7, a washer 13 25 being disposed freely mounted on the screw between said hub 12 and the free leg 5^a of the cleaner. The levers 8 and 11 are bent along a diagonal line so as to form opposing handle 30 portions 8^a and 11^a lying in the same horizontal plane for convenience in operation as herein-after described. A coil spring 14 encircles the screw 7 between the nut 10 and the hub 12 and normally exerts its tension on said hub thereby to resist the tendency of the legs 5^a of the cleaning 35 member to spring apart, the opposite ends of said spring being anchored respectively in the handle portions 8^a and 11^a of the levers 8 and 11.

A thread guide comprising a plate 15 is secured 40 by screws 16 to one of the legs 5^a and is provided with side walls 15^a which overlap the edges of both legs for a portion of their length and thus cover the line where the opposing faces of the legs come together. The openings in the plate 15 through which the screws 16 pass are in the form of slots, 45 as indicated in Figure 2, to permit a certain amount of vertical adjustment of the guide. At their free ends the legs 5^a are provided with flanges 17 bent away from each other to form what may be termed a thread hopper for directing 50 that portion of the thread 18 between the porcelain guides 3 and 4 into the opening between the legs. The said flanges may be formed integral with the legs or secured thereto in any suitable manner.

To ensure the proper cleaning of the thread, the opposing faces of the legs 5^a are maintained in abutting relation when in operation, and each leg is provided in its abutting surface with a series 5 of semi-circular grooves 19, the grooves in the abutting faces thus forming cylindrical openings for the passage of threads. These openings are of sufficiently small diameter, (usually .004 inch) to ensure efficient cleaning of the thread, it being 10 understood, of course, that the diameter of the openings will depend upon the size of the thread to be cleaned. In Figure 3 the diameters are shown greatly exaggerated, for clarity of illustration.

15 In operation, the block 1 is secured on the traverse rail of the usual winding machine. The thread 18, as it passes from one spool to the other is guided through the porcelain guides 3^a and 4^a. The portion of the thread between the guides thus 20 falls between the flanges 17 of the cleaning member. The operator then grasps the handles 8^a and 11^a between his thumb and forefinger and squeezes the handle 11^a toward handle 8^a, thus 25 rotating the nut hub 12 and causing it to recede from the legs 5^a of the cleaning member, against the tension of the spring 14. This permits the legs to separate under their own tension sufficiently to permit the thread to pass between them into one of the cleaning openings, whereupon the 30 handles 8^a and 11^a are released and the tension of spring 14 will reverse the direction of rotation of the nut-hub 12 and cause it to force the legs back into abutting relation, thereby locking the thread in the cleaning opening.

35 From the foregoing it will be obvious that in the device herein described we have provided a thread cleaner in which a pair of cleaning members cooperate to form between them an opening of such configuration as to engage the entire surface of the thread passing therethrough, and which opening is normally inaccessible radially thereof, so that the thread cannot leave the opening during the cleaning operation, nor can a thread be placed in position to be cleaned without first moving one of the cleaning members 40 relatively to the other thereby to render the opening radially accessible.

45 While we have described in detail the embodiments of the invention herein disclosed, it is to be understood that we do not thereby limit our invention to the precise features of construction shown in the drawing, as we are aware that many mechanical changes and modifications may be made therein without departing from the spirit 50 and scope of the invention as set forth in the claims hereto appended.

Having thus described our invention, what we claim is:

55 1. A thread-cleaning device comprising in combination, a base member, a cleaning member secured to said base and having a pair of integral legs disposed in abutting relation and forming between them a radially closed thread-cleaning opening, extending transversely of the legs, one 60 of said legs being automatically movable away

from the other thereby to permit radial access to said opening, and tension means normally maintaining the legs in abutting relation against the action of said movable leg.

2. A thread-cleaning device comprising in combination, a base member, a resilient cleaning member secured to said base and having a pair of parallel legs separable under the resiliency of said member, said legs having in their opposing faces channels cooperating when the legs are in 5 abutting relation to form a radially closed cylindrical opening, and means normally operative to maintain the legs in abutting relation against the separating action of the resilient member.

3. A thread-cleaning device comprising in combination, a base member, a resilient cleaning member secured to said base and having a pair of parallel legs separable under the resiliency of said member, said legs having in their opposing faces channels cooperating when the legs are in 10 abutting relation to form a radially closed cylindrical opening, a member normally exerting tension on said legs thereby to maintain them in abutting relation and means for retracting said tension exerting member thereby to permit separation of 15 the legs under the resiliency of the cleaning member.

4. A thread-cleaning device comprising in combination, a base member, a pair of cleaning members mounted on said base and having parallel 20 opposing faces provided with channels cooperating to form a cleaning opening normally inaccessible radially thereof, one of said cleaning members being resiliently movable to maintain its 25 opposing face out of engagement with the face of its companion member thereby to afford radial access to said opening, and means for normally maintaining said faces in abutting relation.

5. A thread-cleaning device comprising in combination, a base member, a pair of cleaning members mounted on said base and having parallel 30 opposing faces provided with channels cooperating to form a cleaning opening normally inaccessible radially thereof, one of said cleaning members being resiliently movable to maintain its 35 opposing face out of engagement with the face of its companion member thereby to afford radial access to said opening, tension means normally maintaining said faces in abutting relation.

6. A thread-cleaning device comprising in combination, a base member, a resilient cleaning member secured to

40 said base and bent upon itself to provide a pair of parallel legs having in their opposing faces transversely extending channels cooperating to form a 45 radially closed thread-cleaning opening, tension means normally retaining said legs in abutting relation, and means for rendering said tension 50 means ineffective thereby to cause separation of the legs under their own resiliency and afford radial access to said opening.
